UNITED STATES PATENT OFFICE.

CHARLES EIKLER, OF CHICAGO, ILLINOIS, ASSIGNOR, BY MESNE ASSIGNMENTS, TO WIREBOUNDS PATENTS COMPANY, OF NEW YORK, N. Y., A CORPORATION OF MAINE.

BOX-MAKING MACHINE.

1,365,471.

Specification of Letters Patent. Patented Jan. 11, 1921.

Application filed June 21, 1915, Serial No. 35,327. Renewed May 19, 1920. Serial No. 382,691.

To all whom it may concern:

- Be it known that I, CHARLES EIKLER, a citizen of the United States, and a resident of Chicago, in the county of Cook and State 5 of Illinois, have invented certain new and useful Improvements in Box-Making Machines, of which the following is a specification, reference being had to the accompanying drawings.
- 10 My invention relates to box making machines and particularly to that class of machines adapted to form the blank comprising four sides of a wire bound box. It is one of the objects of my invention to provide in a machine of this type new and improved means for feeding forward the cleats or strips which make up the frame of the completed box and to which strips or cleats the thin boards which form the sides of 15 the box are secured by the use of my improved machine. It is one of the objects of my invention to provide a cleat-feeding device such that the cleats shall be fed forward relative to the box blank which is being formed in proper position regardless of 20 the length of the cleat, making it possible to use the machine for making different sized boxes without an adjustment of the cleat-feeding devices.
- 25 It is another object of my invention to provide means for adjusting as desired the length of stitch employed,—that is to say, the length of binding wire between adjacent staples by which the binding wire is secured to the boards forming the sides of the 30 box. It is another object of my invention to provide means by the action of which the staple-forming mechanism is automatically thrown out of effective operation at 35 every joint between the adjacent cleats of the box blank so that the machine is prevented from driving a staple into the cleats at their ends in a position where the staple might interfere with the proper folding of 40 the blank to form a box. It is another object of my invention to provide automatically-acting means adapted to throw out of effective operation the staple-forming mechanism at the time when one completed box 45 blank is passing out of the machine and just before the machine begins to operate upon the succeeding box blank, whereby no staples are formed and fed into the machine in conjunction with the lengths of binding 50

wire which extend between the adjacent blanks and which are employed for tying the blanks in box form.

It is another object of my invention to provide means by which the length of stitch across the board or boards adapted to form 60 one side of the box may be automatically varied relative to the length of stitch across the board forming the adjacent side of the box. As will be readily understood, it is important for the formation of a strong 65 box that a plurality of staples be driven across the board forming each side of a box. In order to accomplish this result it is necessary that the stitch across the short side of a box be comparatively small. If the 70 adjacent side of the box is comparatively much wider, there is no necessity for the use of the same short stitch across the wide side of the box as was important across the short side. I have, therefore, provided automatically-acting means for lengthening the stitch 75 as the wide side of the box comes into position to be stapled and for again automatically shortening the stitch as the short side of the box comes into position to be stapled. 80

It is another object of my invention to provide new and improved means for quickly and easily adjusting a machine of this type for boxes of different lengths. It is another object of my invention to improve 85 machines of this type in sundry details hereinafter pointed out. The preferred means by which I have accomplished the several objects of my invention are illustrated in the accompanying drawings and 90 are hereinafter specifically described. That which I believe to be new and desire to cover by this application is set forth in the claims.

In the drawings:

Figure 1 is a side view of the machine embodying my improvements;

Fig. 2 is a top or plan view of the machine shown in Fig. 1, with the upper portion of the mechanism shown at the right of Fig. 1 broken away for clearness of illustration;

Fig. 3 is a longitudinal vertical section through one side of my improved machine, being taken substantially on line 3—3 of Fig. 2;

Fig. 4 is a longitudinal vertical section through my improved machine, being taken substantially on line 4—4 of Fig. 2;

Fig. 5 is a top view of a box blank of the type adapted to be formed by my improved machine;

Fig. 6 is a very much enlarged detail, taken substantially on line 6-6 of Fig. 3;

Fig. 7 is a fragmentary view, partially broken away, showing the part illustrated in Fig. 6 as seen from above in said figure;

Fig. 8 is a fragmentary view, being a longitudinal section through one of the dogs by which the cleats or strips are fed into position and are spaced relative to each other, being taken substantially on line 8-8 of Fig. 7;

15 Fig. 9 is a view, partly in section, of one of the spacing and feeding dogs, being taken substantially on line 9-9 of Fig. 7;

Fig. 10 is a transverse vertical section of the dog shown in Fig. 9, being taken substantially on line 10—10 of Fig. 9;

Fig. 11 is a diagrammatic view illustrating in part the means for throwing out of effective operation the staple-forming mechanism, and illustrating in part the clutch mechanism employed in connection with the means for varying the length of stitch between adjacent wide and narrow sides of a box blank;

Fig. 12 is a view showing the means for feeding the staple wire;

Fig. 13 is an enlarged detail taken substantially on line 13-13 of Fig. 12;

35 Figs. 14 and 15 are diagrammatic side views of the mechanism by which the length of stitch is varied for the wide and narrow sides of the box, Fig. 14 showing the mechanism in position for a short stitch, and Fig. 15 showing the mechanism in position for a comparatively longer stitch;

40 Figs. 16 and 17 are diagrammatic views showing the variation in the throw of the pawl which operates the mechanism by which the box blank is fed forward, Fig. 16 illustrating diagrammatically the operation of the mechanism when in the adjustment shown in Fig. 14, and Fig. 17 illustrating diagrammatically the operation of the mechanism when in the adjustment shown in Fig. 15:

50 Fig. 18 is an end view, as seen from the right in Fig. 1, of the mechanism by which the stitch-varying devices are operated;

Fig. 19 is a section taken substantially on line 19-19 of Fig. 18;

55 Fig. 20 is a section taken substantially on line 20-20 of Fig. 19;

Fig. 21 is a section taken substantially on line 21-21 of Fig. 19; and

Fig. 22 is a perspective view of the cam device shown in Fig. 19 forming a part of the clutch device employed in connection with the mechanism for varying the length of stitch between the wide and narrow sides of the box blank.

Referring to Fig. 5 of the drawings which 65
illustrates the form of box blank which my
improved machine is designed to form, it
will be noted that the blank is made up of
four sections each comprising two cleats or
strips spaced apart and joined by a sheet or 70
board, the four sections being joined to-
gether by binding wires 30 secured to the
boards by staples 31. In the box blank
shown, the adjacent sections forming the
blank are different in size, the cleats and 75
boards entering into the formation of the
wider sections being indicated by the numer-
als 32 and 33, respectively, and the cleats
and boards entering into the formation of
the narrower sections being indicated by the 80
numerals 34 and 35, respectively. The staples
31 by which the binding wires 30 at the
ends of the sections are secured to the boards
are of a length such as to pass well into the
cleats or strips, while the staples 31 by 85
which the intermediate binding wires 30 are
secured to the boards are shorter, being
adapted to pass through the boards and
have their ends offset or clenched.

My improved machine for forming a blank of the general type shown in said Fig. 5 comprises means for forming and driving the staples 31, together with means for feeding step by step into proper position for the staple driving operation the elements entering into the formation of the blank. In the embodiment of my invention as illustrated in the drawings, I have employed a main driving shaft so connected up with the operative parts of the machine that normally the blank is advanced one step and one row of staples is driven for each complete revolution of the shaft. The arrangement is such that the wire out of which the staples are formed is fed forward during the latter portion of the inoperative stroke of the cross-head by which the staple driving devices are operated, the operation of advancing the staple wire taking only a comparatively small portion of the time of a complete revolution of the main shaft. The arrangement is such that the effective forwarding operation of the means for advancing the box blank takes up the time of a half revolution of the main shaft, the blank-forwarding operation starting soon after the beginning of the upward inoperative stroke of the cross-head by which the staple driving devices are operated, and continuing until such cross-head is well started upon its downward operative stroke. By this arrangement and timing of the parts, the staple wire is advanced to the staple forming mechanism in ample time for the forming and placing in position of a staple and the subsequent driving of the staple upon the operative downward stroke of the cross-head; and the partially-formed blank is advanced into position 90

95

100

105

110

115

120

125

tion to receive a transversely-extending row of staples in due time well before the end of the operative stroke of the cross-head.

In my improved machine, the elements 5 making up the blank are fed forward by power applied to the cleats or strips 32-34, the binding wires being pulled forward by reason of their attachment to the cleats or strips of the blank being formed. At the 10 commencement of the formation of any given blank during the continuous operation of the machine, the binding wires are pulled forward by reason of their connection with the previously-formed box blank. 15 The means for feeding the cleats or strips 32-34 forward at each side of the machine comprises four dogs or carrier-blocks which are adapted to be drawn forward by an endless chain, the two chains so provided being 20 driven intermittently in unison to provide the proper intermittent forwarding of the dogs. The dogs are moved by the chains beside suitable slideways along which the cleats or strips 32-34 are slidable, the dogs 25 serving not only to forward the cleats but also to space the cleats properly relative to each other. One of the dogs is of considerably greater length than the remaining three dogs, the longer dog being employed 30 for providing the proper spacing between successively-formed blanks so as to provide proper lengths of binding wire for tying purposes for securing the ends of the blank together when folded into box form. Auxiliary 35 means is provided for carrying the dogs at each side of the machine from the forward end of the slideway out of position between the cleats with which it has been moving to the rear end of the slideway for 40 spacing and forwarding the corresponding cleats of the next-succeeding blank. This auxiliary forwarding means in my machine comprises endless chains driven constantly adapted to carry the dogs at a 45 greater effective speed than that of the blank-forwarding chains, so that the dogs shall be in proper position at the rear end of the slideway when needed. In the operation 50 of the machine, the slideways are kept filled with cleats in the proper spaced relation. As one of the dogs passes along the slideway actuated by the fast-moving chain so as to leave room in the slideway for the 55 proper cleat or strip 32-34, such cleat or strip is placed by an operator in position in the slideway. The next-succeeding dog brought up by the fast-moving chain carries the cleat so placed in the slideway forward into proper spaced relation to the cleat last- 60 previously placed in the slideway, these successive operations continuing in rotation during the operation of the machine. The arrangement is such that the fast-moving chains are adapted to automatically pick up 65 and carry around any one of the dogs soon

after it is released from a blank, the connection between the fast-moving chains and the dog continuing until the progress of the dog is stopped by reason of the cleat being forwarded thereby being brought into contact 70 with the slower-moving blank.

Referring now to the several figures of the drawings, in which corresponding parts are indicated by like reference characters,—

36-37 indicate standards joined by 75 heavy cross-bars 38-39, the cross-bar 39 being preferably adjustable vertically upon the standards in any suitable manner. Two heavy side-plates 40-41 are fixed at their forward ends upon the cross-bar 39 at one 80 side of the machine, and two similar side-plates 42-43 are slidably mounted at their forward ends upon the heavy cross-bar 39 at the opposite side of the machine, the plates at each side of the machine being spaced 85 away from each other a short distance, as shown in Fig. 6. The rear ends of the plates 40-41 are fixed upon a heavy supporting bar 44 which passes through said plates, and the rear ends of the side-plates 42-43 90 are slidably mounted upon said supporting bar, standards 45-46 being provided for supporting the bar 44 at its ends. Two transverse shafts 47-48 are revolvably mounted in the plates 40-41 and held 95 against movement transversely of the machine, said shafts having screw-threaded connection with the plates 42-43. The said two shafts are connected by means of a sprocket chain 49, whereby they are caused 100 to rotate in unison. A crank-handle 50 is adapted to be mounted upon the shaft 47 for turning the shafts 47-48, as will be readily understood, for sliding the side-plates 42-43 laterally toward the side- 105 plates 40-41.

In the construction shown the main drive shaft 51 by which the blank forwarding and staple forming and driving mechanisms are driven is revolvably mounted between the 110 standards 36-37 near their lower ends. Said shaft 51 is driven by another shaft 52 through the medium of intermeshing gears 53-54, the shaft 52 being driven by a motor 55 through the medium of intermeshing 115 gears 56-57. A foot lever 58 and suitable clutch-mechanism of any suitable type are provided for connecting the gear 53 with the shaft 51, the arrangement in the construction shown being such that the gear 53 is 120 adapted to rotate the shaft 51 when the lever 58 is held in its lowered position. As will be readily understood, when the lever 58 is released the connection between the shaft 51 and the gear 53 is automatically 125 terminated. The shaft 52 is provided with speed-changing mechanism of any suitable type located in the transmission box 59 whereby the sprocket-wheel 60 may be driven at varying speeds relative to the 130

shaft 52. The transmission mechanism in the box 59 is also provided with a suitable disconnecting clutch adapted to be operated through the medium of a rod 61 provided with a lever 62 at the rear end of the machine. Inasmuch as these devices are well understood in the art and form no part of my present invention it is believed to be unnecessary to further describe or illustrate them.

The inner side-plate at each side of the machine has formed integrally with it two upwardly-extending flanges 63 providing thus a slideway for the cleats or strips 32—34. The opposite edges of the side-plates are rabbeted out along their adjacent faces to provide a slide way for the dogs or carrier-blocks 64, plates 65 and 66 being mounted upon the upper and lower edges, respectively, of each of the outer side-plates for the purpose of preventing the dogs 64 from escaping from their slideways. Mounted upon each of the plates 65 of the outer side-plates are a plurality of brackets 67 which extend inwardly from the plate 65 upon which they are mounted, and support upon their inner ends a longitudinally-extending guide rail 68, the inner face of which is in vertical alinement with the inner face of the outer flange 63. Each of the dogs 64 is provided with a cam lug 69 upon its upper face for the purpose hereinafter set forth, from the inner face of which lug there extends inwardly an arm 70 carrying upon its inner end a spacing block 71 which is adapted to space adjacent strips 32—34 from each other, as is clearly shown in Fig. 7.

Adjustably mounted upon the rear end of each of the outer side plates is an extension plate 72 upon which is revolvably mounted a drum 73. The periphery of the drum 73 is provided with a suitable circumferential groove through which the dogs 64 are adapted to pass, being held in position in the groove of the drum by means of a circular flange 74 formed on the plate 72 about the drum 73. The drum 73 and flange 74 serve thus to connect the upper slideway provided by the side-plates for the dog 64 with the similarly-formed slideways in their lower edges. Extension-plates 75 are connected with the outer side-plates 40 at their forward ends, the plates 75 having drums 76 revolvably mounted thereon. The drums 76 are likewise provided with circumferential grooves adapted to provide a path for the dog 64 from the upper slideway to the lower slideway at the forward end of the machine, the plate 75 being provided with flanges 77 for retaining the dogs in position in their movement about the drum.

For carrying the dogs 64 about the endless slideway thus provided I have provided two pairs of fast-moving endless chains 78,

one pair for the slideway provided by the side-plates at each side of the machine. The chains 78 are mounted at their rear ends upon suitable sprocket-wheels provided by the drum 73 on opposite sides of the circumferential groove in said drum, and the chains are supported at their forward ends by sprocket-wheels formed upon the drums 76, as shown in Figs. 3 and 4. The drum 76 mounted adjacent to the extension-plate 75 which is secured to the side-plate 40 is fixed upon a transversely-extending shaft 79 for its support relative to such extension-plate, while the drum 76 at the opposite side of the machine is feathered upon said shaft so as to be rotated thereby, but so as to be adjustable longitudinally of the shaft as the side-plates 42—43 are adjusted for different sized boxes. As will be seen by an inspection of Figs. 1 and 2, the shaft 79 has fixed upon one end a sprocket wheel 80 which is connected by a sprocket-chain 81 with the sprocket-wheel 60 which is adapted to be driven at variable speed by the shaft 52 through the medium of the variable gearing of the transmission box 59, as above described. As will be readily understood, the direction of rotation of the motor 55 is such as to cause the shaft 52 to be driven in clockwise direction in Fig. 1, serving to cause such a revolution of the chains 78 as to move the dogs 64 forward or to the right in Fig. 2 in the upper slideways.

The means for yieldingly connecting the dogs 64 to the chains 78 so as to cause the dogs to be forwarded by the chains comprises lugs 82 extending from the adjacent faces of the chains 78 of each pair of chains, a plurality of pairs of such lugs being provided along the chains. For coöperation with the lugs 82 of the chains 78, each of the dogs 64 is provided with spring latch devices 83. As best shown in Fig. 10, the latch devices 83, in the construction shown, are made in the form of pins slidably mounted in a transversely-extending opening 84 through the dog, a spring 85 being interposed between the pins 83 for holding the pins yieldingly in their extended positions. Keys 86 are mounted in the dog working in suitable slots in the pins for limiting the outward movement of the pins. As best shown in Figs. 7 and 10, the pins or latches 83 are beveled at their outer ends, the lugs 82 being similarly beveled as shown in Fig. 7. As will be readily understood, when one of the dogs or carrier-blocks 64 is released from engagement with a box blank at the forward end of the machine, such dog is free to pass about the slideway, as above described. As soon thereafter as a pair of the lugs 82 carried by the chains 78 is brought into contact with the latches 83 of such dog as is shown in Fig. 7, the chains 78 serve to carry the dog 64 around through the slideway. When the

dog 64 comes in contact with a cleat or strip 32 or 34 placed in position between the flanges 63 as above described, the dog 64 serves to move the cleat or strip forward until the cleat is brought into contact with the preceding dog 64. The latches 83 then yield inward permitting the chains 78 to continue their revolution, the dog 64 being thereafter controlled in its movement by the advance of the blank irrespective of the fast-moving chains 78. As the lugs 82 carried by the chains 78 come in contact with the latches 83 of the various dogs 64 in engagement with the box blank in process of formation, the latches 83 yield inward so as to permit the chains to pass. By the use of the variable speed mechanism of the transmission box 59, the speed of the chains 78 can be varied so as to cause the dogs 64 to be brought up into position as desired.

The means for intermittently forwarding the box blank into position for the reception of successive rows of staples 31 comprises two endless chains 87, one of such chains being mounted between the side plates at each side of the machine. Each of these chains is supported at its rear end by a sprocket-wheel 88 mounted upon a short shaft 89 which is adjustably mounted relative to the side plates by means of bearing plates 90, as shown in Figs. 1 and 4. The forward end of the chain 87 mounted between the side plates 40-41 is supported by a sprocket-wheel 91 fixed upon a shaft 92 which is suitably journaled in the side-plates of the machine. The forward end of the chain 87 which is positioned between the side-plates 42-43 is supported by a similar sprocket-wheel 91 which is feathered upon the shaft 92 to provide for the lateral adjustment of the side-plates 42-43 as above described. The chains 87 are thus adapted to be driven in unison upon the rotation of the shaft 92, as hereinafter described. An inwardly-extending plate 93 formed with the outer side-plate serves to support the upper portion of the chain 87 between the sprocket-wheels 88-91. The dogs 64 are connected with the chains 87 for actuation thereby through the medium of pawls 94 which are pivotally mounted in the rear ends of the dogs by means of pivot pins 95. Springs 96 are mounted upon the dogs 64 adapted to hold the pawls 94 yieldingly in contact with the chain 87, the outer face of which is notched, as best shown in Fig. 3, for the reception of such pawls. Pivotally mounted upon the pin 95 adjacent to the pawl 94 is a second pawl 97 which is adapted to be held yieldingly by a spring 98 in contact with the teeth of a rack 99 fixed in position above the plate 93, as best shown in Fig. 6. The spring 98 is adapted to act upon the pawl 97 through the medium of a pin 100 extending laterally from the pawl 97, the

pin 100 also extending over a portion of the pawl 94 whereby an upward movement of the pawl 94 out of operative contact with the chain 87 serves to move the pawl 97 simultaneously out of operative contact with the rack 99. By the use of the rack 99 the dogs 64 are prevented from slipping backward upon the rebound which occurs upon the release of the dog from the fast-moving chains 78.

As is set forth above, one of the dogs 64 is considerably longer than the other three dogs to provide a proper spacing between successively-formed complete blanks. The long dog 64, as is shown in Figs. 3 and 4, is made up of two sections pivotally connected together by means of a link 101 so as to permit the said dog to pass about the drums 73-76. The rear section of the long dog is provided with the spring-latch mechanism and the pawl mechanism as has been described.

For steadyng the cleats 32-34 as they pass along the slideway under the staple driving mechanism I have provided a plurality of rollers 102. These rollers are milled on their edges and are revolubly mounted adjacent to the slideways in which the cleats are moved so as to engage the inner faces of the cleats. As the cleats are advanced past the rollers 102 the rollers are caused to rotate by their frictional engagement with the cleats. Means is provided for causing all of the rollers 102 to rotate in unison whereby the cleats are very materially steadied in position. The means for supporting the rollers 102 and for causing them to rotate in unison comprises a shaft 103 extending transversely of the machine and journaled in the side-plates, having bevel gears 104 mounted thereon, the gear 104 adjacent to the side-plate 41 being fixed upon the shaft 103 and the gear 104 mounted upon the shaft 103 adjacent to the side-plate 43 being feathered on said shaft. Meshing with the gears 104 are other bevel gears 105 mounted upon shafts 106 suitably supported below the rollers 102. Each of the rollers 102 is mounted upon a shaft 107 connected by means of bevel gears 108-109 with the shaft 106 (see Fig. 4). The spur-rollers 102 are thus caused to rotate in unison.

The means for forming and driving the staples 31 for securing the binding wires 30 in position comprises a cross-head 110 slidably mounted in suitable slots 111 in the upper ends of the standards 36-37. The cross-head 110 is reciprocated up and down by means of connecting rods 112 connected at their upper ends to said cross-head and operatively connected at their lower ends with eccentrics 113 fixed upon the main drive-shaft 51. The cross-head 110 is thus adapted to be given a complete inoperative

upward stroke and a complete operative downward stroke upon each rotation of the shaft 51. The cross-head 110 is provided with a plurality of plungers 114 adjustably mounted upon the cross-head adapted to coöperate with suitable staple-forming and driving devices 115 adjustably supported upon the cross-bar 48. For the formation of the blank shown in Fig. 5, there will be five of these staple forming and driving mechanisms, together with five of the plungers 114, as will be readily understood. The staples 31 are adapted to be formed by the mechanism out of staple wires 116 which are adapted to be fed to the staple forming mechanism by the means hereinafter described, there being as many wires 116 as there are binding wires 30, as will be readily understood. It will be appreciated that a staple 31 is formed and driven upon each operative downward stroke of the cross-head 110 unless there has been a failure to feed the staple wires 116 to the staple forming devices. In case of such a failure to feed the wires 116, the staple forming and driving mechanisms pass through their several evolutions without having any effect upon the blank or upon the machine. Inasmuch as the staple forming and driving mechanisms may be of any approved type it is not believed to be necessary to further illustrate or describe them, the only feature in connection with these devices which forms a part of my present invention being the means for controlling the feed of the staple wires 116, as hereinafter fully described.

The plungers 114 and the coöperating staple forming and driving mechanisms 115 are adapted to be adjusted upon the cross-head 110 and the cross-bar 38 in proper position for placing the binding wires 30 in the desired position upon the boards 33-35 of the blank. The outer sets of mechanisms 114-115 are designed to drive staples 31 into the cleats 32-34 and are, of course, adjusted relatively to said cleats. For the purpose of clinching the staples 31 driven by the intermediate coöperating staple mechanisms 114-115, I have provided anvils or shoes 117 adjustably mounted upon the cross-bar 39 so as to be adjusted to proper position relative to the staple driving elements. As the width of the cleats 32-34 or the thickness of the boards 33-35 are varied for different boxes, the cross-bar 39 is adjusted up and down relatively to the standards 36-37, as above described, so as to bring the point of driving the staples 31 to the proper height relative to the mechanisms 114-115. The rear end of the machine may then be correspondingly adjusted if desired by an adjustment of the standards 45-46.

The means for intermittently forwarding the staple wire 116 (see especially Figs. 4, 11, 12 and 13) comprises a shaft 118 revolu-

bly mounted in suitable brackets 119 extending rearwardly from the standards 36-37. Revolubly mounted upon the shaft 118 adjacent to the standard 36 are two levers 120-121 connected at their forward ends by 70 means of a pin 122 with the upper end of a link 123. The lower end of the link 123 is in the form of a yoke which straddles the main drive-shaft 51, being provided with a stud 124, preferably in the form of a roller, 75 adapted to be engaged by a cam 125 fixed upon the shaft 51. A spring 126 connects the link 123 with the framework of the machine tending to hold the link 123 yielding in its lowermost position. A pin 127 80 is carried by the levers 120-121 at their rear ends, having mounted thereon a pawl 128 and a spring 129 serving to hold the pawl yielding in its raised operative position in engagement with the teeth of a 85 ratchet wheel 130 fixed upon the shaft 118 between the levers 120-121. Revolubly mounted upon the shaft 118 adjacent to the ratchet 130 is a sleeve 131 provided with a cam 132 which is adapted to be moved downward, by a counterclockwise turning of the sleeve 131 in Fig. 13, into engagement with a pin 133 projecting from the face of the pawl 128 for throwing the pawl out of operative engagement with the ratchet-wheel 95 130 as hereinafter described. By the use of the devices described, upon each rotation of the shaft 51 the link 123 will be moved upward by the cam 125 against the action of the spring 126, turning the levers 120-121 100 in counterclockwise direction in Figs. 11 and 13 and causing a similar part revolution of the shaft 118. It will be understood, however, that if the sleeve 131 were rotated in counterclockwise direction in Fig. 13 so as 105 to cause the pin 133 to ride up the cam 132, the upward movement of the link 123 and the counterclockwise movement of the levers 120-121 would then have no effect upon the ratchet 130 and the shaft 118. Extending rearwardly from the frame portion of each of the staple forming and driving mechanisms 115 is an arm 134 as shown in Fig. 4, only the bifurcated rear end of such arm being shown in Fig. 12. Feathered upon 110 the shaft 118 and located between the two arm-portions is a milled roller 135 having connected with it a gear 136, with which meshes another gear 137 mounted upon a pin 138 extending laterally from the arm 115 120 134. Fixed so as to rotate with the gear 137 is a milled roller 139 adapted to coöperate with the milled roller 135 for forwarding the staple-wire 116. In order to provide a greater length of wire for the staples 31 125 which are driven into the cleats or strips of the box blank the staple wire forwarding mechanisms which feed the wire to the outermost staple forming mechanisms employ larger rollers 135 than those used in connec- 130

tion with the intermediate staple forming mechanisms, as will be readily understood.

The means for throwing the staple wire forward device out of operation during one operative stroke of the cross-head 110 when one cleat 32 or 34 is passing out of position for receiving a staple and before the next cleat 34 or 32 is in position to receive a staple, comprises a lever 140 pivotally mounted upon the plate 65 carried by the sideplate 40 provided with a stud or roller 141 in position to be engaged by the cams 69 of the dogs 64. In Fig. 11 I have indicated in dotted lines a dog 64 about to engage the roller 141 for throwing the lever 140 upward. The forward end of the lever 140 is connected by means of a link 142 with an arm 143 extending rearwardly from the shaft 144 mounted in the brackets 119 and extending transversely of the machine. The shaft 144 is provided with a downwardly extending arm 145 fixed thereon adjacent to the bracket 119 mounted upon the standard 36, said arm 145 being connected by a link 146 with an arm 147 mounted upon the sleeve 131. As will be readily understood, when a box blank approaches the position at which the last staple is to be driven into one of the cleats 32 or 34 the dog 64 between that cleat and the next-succeeding cleat is brought into contact with the roller 141 which rides up the cam 69 upon the advance of the dog with the blank. This serves to rotate the shaft 144 in clockwise direction in Fig. 11, throwing the arm 147 in counter-clockwise direction in said figure and throwing the pawl 128 out of operative position, as has been above described, serving to prevent the feeding of the staple wires 116. The position of the roller 141 in the path of the dog 64 is such that the throwing out of operation of the pawl 128 is so timed as to cause the crosshead 110 and the staple forming and driving apparatus actuated thereby to be given an operative stroke without a corresponding feeding of the staple wires, with a result that no staple is driven. When the long dog 64 passes under the roller 141 the pawl 128 is held out of operation during a plurality of operative strokes of the cross-head 110 for preventing the formation of any staples for the lengths of wire between adjacent blanks. As soon as the dog 64 passes out of contact with the roller 141 the parts assume their normal position in condition for effective operation.

The means for rotating the shaft 92 in clockwise direction in Fig. 4 for causing an intermittent movement of the chains 87 comprises a connecting rod 148 mounted by means of a crank 149 upon the shaft 51 eccentrically thereof. A lever 150 (see Figs. 1, 14 and 15) is fulcrumed upon a slide-block 151 which is mounted upon a pivotally-mounted arm 152 adapted to be held

adjustably in position, as hereinafter described. The block 151 is adapted to be adjusted along a longitudinally-extending slot 153 in said lever by an adjustment of the pivotally-mounted arm 152, as herein-after described. A pin 154 connects the upper end of the connecting rod 148 with the forward end of the lever 150 and with the rear end of a pivotally-mounted link 155, the arm 155 serving to permit the lever 150 to be reciprocated up and down upon the fulcrum-block 151, but to hold it in proper position longitudinally of itself. The rear end of the lever 150 is connected by means of a link 156 with an arm 157 which is mounted upon a short rock-shaft 158, with which it is adapted to be rocked. As is shown in Fig. 16, the short rock-shaft 158 has mounted upon it and extending upwardly therefrom a rock-arm 159 to the upper end of which is pivotally connected a link 160. The forward end of the link 160 is pivotally connected by means of a pin 161 with the upper end of an arm 162 revolvably mounted upon the shaft 92 adjacent to a ratchet-wheel 163 feathered upon said shaft. A pawl 164 is also pivotally mounted upon the pin 161, whereby upon a stroke of the arm 159 in clockwise direction in said Fig. 16 the ratchet-wheel 163 and the shaft 92 will be rotated in the same direction, the extent of the rotation of the ratchet 163 and the shaft 92 depending upon the size of the angle through which the arm 159 is rocked. As will be readily understood, upon the rotation of the shaft 51 the connecting rod 148 will be reciprocated up and down causing the lever 150 to swing upon the fulcrum-block 151, and causing the arms 157 and 159 to be rocked back and forth with a consequent rotation of the shaft 92. The arrangement is such that the shaft 92 will be rotated upon the downward movement of the connecting rod 148.

As will be readily understood, the distance through which the rear end of the lever 150 is adapted to be moved when actuated by the uniform movement of the connecting rod 148 depends upon the position of the fulcrum-block 151 between the ends of the lever. As the fulcrum-block 151 is moved to the right in Figs. 14 and 15 the extent of the movement of the rear end of the lever 150 upon an actuation of said lever through the connecting rod 148 will be increased with a corresponding increase in the extent of rotation of the shaft 92 and a similar increase in the extent of movement of the chains 87 and the box blank carried forward thereby. It is thus apparent that by adjusting the arm 152 the distance between staples along the binding wires 61 can be varied as desired. The means for adjusting the arm 152 for varying the distance between staples comprises a socket member 165 pivotally

- connected with the upper end of the link 152, a socket member 166 adapted to be fixed relative to the standard 36, and a rod 167 having screw-threaded connection with said 5 two sockets for drawing them together or for moving them away from each other, as may be desired. The manner of mounting the socket member 166 relative to the standard 36 by which an additional function is 10 performed will be hereinafter described, but it will be understood that the distance between staples can be varied by an adjustment of the screw-threaded rod 167 quite independently of the additional function 15 hereinafter described.

As has been set forth above, means is provided for automatically varying the stitch so as to have the staples 31 farther apart across the wide side of the box than across 20 the narrower side. This is accomplished by a shifting of the arm 152 and the fulcrum-block 151 upon each change of the box blank from a position for driving staples in one side to the position for driving staples in the 25 next-adjacent side. That is to say, as the box blank is moved forward to bring a short cleat into position to receive a staple the arm 152 is to be automatically moved to the left in Figs. 14 and 15. When the blank 30 is thereafter moved into position to have staples driven into one of the longer cleats, the arm 152 is moved to the right in said figures to increase the distance between staples.

- 35 The means for accomplishing this result comprises a rotatable plate 168 to which the socket 166 is pivotally connected, together with means for revolving said plate comprising clutch mechanism for stopping the rotation of the plate at the end of each half revolution thereof, the socket 166 being 40 adapted to be connected to the plate 168 eccentrically thereof whereby a rotation of the plate serves to swing the arm 152. As best 45 shown in Fig. 18, the plate 168 is mounted upon a short shaft 169 suitably supported by the standard 36. The plate 168 is provided upon one face with a radially-extending slot 170, at any point along which the socket 50 166 is adapted to be revolvably secured by means of a bolt 171. Mounted upon the shaft 169 is a gear 172 which meshes with a gear 173 which is fixed upon a short shaft 174 revolvably mounted upon the standard 36. Revolvably mounted upon the shaft 174 adjacent to the gear 173 is a sprocket-wheel 175 which is driven continuously by a sprocket-chain 176 working upon a sprocket-wheel 177 mounted upon one end of the shaft 55 172. The gear 172 is of just twice the diameter of the gear 173, whereby the gear 172 and the plate 168 are adapted to be given a half revolution by a single complete revolution of the gear 173. Suitable clutch mechanism is provided for connecting the gear 173
- and the sprocket-wheel 175, such clutch mechanism being adapted to be automatically thrown out of operation at the end of one complete rotation of the gear 173. The means for throwing the clutch again into operation for causing another complete rotation of the gear 173 comprises an arm 178 extending upwardly and forwardly from the shaft 144, having connected to its upper end a thrust-bar 179 by a downward stroke 75 of which the clutch is thrown into operation for rotating the plate 168. The arrangement will be seen to be such that upon the passage of one of the dogs 64 under the roller 141 the link 179 will be given an op- 80 erative downward stroke for causing a half rotation of the plate 168. As will be readily appreciated, by the use of the mechanism just described the stitch across the narrow side of the box may be made as short as de- 85 sired relative to the length of stitch along the wide side of the box, the socket 166 being adjusted as far as may be desired from the center of the plate 168 so as to produce the desired variation. As a dog 64 spacing apart 90 a cleat 32 from a following short cleat 34 passes under the roller 141 the plate 168 will be given a half revolution, swinging the arm 152 to the left into the position shown in Fig. 14 so as to give the arm 159 a 95 short rocking motion, as indicated by the arrow in Fig. 16. When the next-succeeding dog 64 passes under the roller 141 bringing a long strip 32 and the corresponding wide board 33 into position to receive the staples, 100 the plate 168 will be given another half revolution into the position shown in Fig. 15, whereupon the arm 159 will be given a correspondingly longer stroke for a correspondingly longer stitch between the rows of 105 staples 31.
- The clutch which is actuated by the link or thrust-bar 179 for connecting the gear 173 with the sprocket wheel 175 comprises a spring-actuated pin 180 carried by the gear 110 173 adapted to be projected into a suitable socket 181 in the sprocket-wheel 175 for causing the gear 173 to rotate with said sprocket-wheel. In the construction shown, the pin 180 is provided with a key or pin 115 182 projecting from one side thereof adapted to work in a groove 183 in the gear 173 for holding the pin 180 against turning. A spring 184 is interposed between the pin 182 and one end of the groove 183 tending to 120 hold the pin 180 in its extended operative position. For holding the pin 180 in its retracted position out of engagement with the socket 181 I have provided a cam plate 185 slidably mounted in a bracket 186 suitably mounted upon the standard 36. The inner end of the cam-plate 185 is adapted to work in a circumferential groove 187 in the gear 173, a spring 188 being provided connecting the cam-plate 185 to the bracket 186 tend- 125 180

ing to hold the plate 185 yieldingly in operative position with its inner end in engagement with a suitable notch in the pin 180 so as to hold the pin 180 in its retracted 5 position, as shown in Fig. 21. Pivottally mounted upon the bracket 186 (see Fig. 11) is a bar 189, said bar having also a pivotal connection with the plate 185, sufficient play being provided in the connections of the bar 10 189 to provide for a slight sliding movement of said plate. As is clearly shown in Fig. 11, the lower notched end of the link or thrust-bar 179 engages the upper face of the bar 189.

15 As will be readily understood, upon a downward stroke of the thrust-bar 179 actuated by an upward movement of the roller 141 and the lever 140 under the influence of the dog 64 passing under said roller, the 20 link 189 is given a slight downward movement on its pivotal mounting, moving the plate 185 downward. This movement serves to release the pin 180 which is then free to be projected by the spring 184 into engagement 25 with the socket 181 as soon as such socket is brought into proper alinement, whereby the gear 173 is caused to rotate. When the thrust-bar 179 is drawn upward by reason of the dog 64 passing out of position 30 under the roller 141, the plate 185 is brought again to its operative position by the spring 188. Just before the end of a complete revolution of the gear 173 in clockwise direction in Fig. 19, the notch in 35 the pin 180 is brought into engagement with the operative cam face 190 of the cam plate 185 by which the pin 180 is retracted out of engagement with the socket 181 permitting the gear 173 to come to rest.

40 In order to insure the gear 173 being given only a single revolution upon each actuation of the thrust-bar 179, whether or not the dog 64 is withdrawn from engagement with the roller 141 during the rotation of 45 the gear 173, I have provided means operative before the end of one complete revolution of the gear 173 to throw the thrust-bar 179 out of engagement with the bar 189 whereby the cam-plate 185 is permitted 50 to return to operative position irrespective of the position of the thrust-bar 179. This means comprises a cam 191 carried around by the gear 173 adapted to be brought into engagement with a stud or roller 192 mounted 55 upon the thrust-bar 179 whereby the said thrust-bar 179 is swung to the left in Fig. 11 against the action of a spring 193 which tends to hold the said thrust-bar at the limit of its movement to the right in said Fig. 60 11. The cam 191 is preferably to be so positioned as to act upon the thrust-bar 179 just before the pin 180 is brought into engagement with the cam face 190 of the cam-plate 185, serving to displace the thrust-bar 179 at the latest available moment before the end of the complete revolution of the gear 173. Upon the continued rotation of the gear 173 while the pin 180 is being retracted from the socket 181, the cam 191 will be rotated out of position engaging the 70 roller 192, as will be readily understood. In case the thrust-bar 179 has been drawn upward so as to release the bar 189 and the cam-plate 185 from their inoperative position before the cam 191 is brought into position to engage the roller 192, the displacement of the bar 179 to the left in Fig. 11 by the cam 191 will have no effect upon the mechanism, the bar 179 being adapted to be brought back by the spring 193 into engagement with the bar 189 upon the passage of the cam 191 out of engagement with the roller 192.

75 It is believed that the operation of the machine as a whole will be fully understood 80 without further detailed description. As will be readily understood, with an operator holding the foot lever 58 down so as to connect the continuously-driven gear 53 with the main shaft 51, the apparatus will 85 be operated as has been described. An assistant at the rear end of the machine places the cleats or strips 32-34 in the slideways at both sides of the machine, one strip being placed in position following each of the 90 dogs 64 as it is brought up by the fast-moving chains 78. The operator places the boards 33-35 in position upon the cleats 32-34 between the guide rails 68 as the properly spaced cleats 32-34 are intermittently fed forward by the chain 87. Another assistant at the forward end of the machine cuts the binding wires 30 between the blanks after a sufficient number of rows 95 of staples 31 have been driven into the new 100 blank to hold the binding wires 30 against slipping relative to the new blank.

105 As will be readily understood from an inspection of my improved machine, it will be appreciated that the machine is adapted 110 without any adjustment whatever to make box blanks of various sizes and proportions. All that is necessary for forming a blank for a box of one size is to feed to the machine box blank materials of the proper proportions. If, after the completion of a box 115 blank of one size, box blank elements for a blank of a different size are fed into the machine without even stopping the continuous operation of the machine a blank of a 120 different size would be formed corresponding to the character of the elements fed to the machine. As has been above described, it is necessary to adjust the machine for producing blanks for boxes of varying 125 lengths, and it is also sometimes necessary, as before described, to adjust the cross-bar 39 vertically, but for varying the width or depth of boxes no adjustment whatever is necessary or advisable unless it be a change 130

of speed of the fast-moving chains by a simple adjustment of the mechanism of the transmission box 59.

While I have described the chains 78 as being fast-moving chains and the chains 87 as being comparatively slow-moving chains, it will be understood that I mean that the chains 78 are fast-moving as compared to the aggregate effective movement of the 5 chain 87. The movement of the chain 87 being intermittent, the actual speed of movement of the chain 87 during the time the chain is moving is immaterial. It might well be that the chains 87 during their 10 movement would move faster than the chains 78. The essential feature is that the chains 78 have during a certain time a sufficiently greater movement than the aggregate movement of the chains 87 during that 15 time that the dogs 64 will be brought to proper position as above described. The terms fast-moving chain and slow-moving chain are used, therefore, in the specification and claims with reference to the aggregate movement rather than with reference to the actual speed of movement at any given instant.

What I claim as my invention and desire to secure by Letters Patent, is—

30 1. In a box blank making machine, the combination of a chain, carrier-blocks arranged to be actuated by said chain for moving a blank forward in the process of formation, and a faster-moving chain constructed and arranged to move said carrier-blocks, when released from engagement with one blank, into operative position for forwarding another blank.

40 2. In a box blank making machine, the combination of an endless chain, means for intermittently driving said chain, carrier-blocks arranged to be actuated by said chain for moving a blank forward in the process of formation, a second endless chain, and 45 means for driving said second chain at a greater rate of revolution, said second chain being constructed and arranged to move said carrier-blocks, when released from engagement with one blank, into operative 50 position for forwarding another blank.

55 3. In a box blank making machine, the combination of positively-acting means comprising carrier-blocks adapted to move a blank forward intermittently, and other faster-moving means constructed and arranged to have yielding connection with said carrier-blocks independently of the positively-acting intermittent driving means for moving them successively, when released 60 from engagement with one blank, into operative position for forwarding the next-succeeding blank.

65 4. In a box blank making machine, the combination of positively-acting means adapted to move a blank forward, spacing-

blocks by which the cleats of the blank are properly spaced relative to each other, and means adapted to have yielding connection with said spacing blocks independently of the positively-acting forwarding means for 70 moving them successively, when released from engagement with one blank, into operative position for spacing the cleats of a succeeding blank.

5. In a box blank making machine, the 75 combination of a chain, carrier-blocks arranged to be positively actuated by said chain for moving a blank forward, and a faster-moving chain constructed and arranged to have yielding connection with 80 said carrier-blocks for moving them successively, when released from engagement with one blank, into position for forwarding another blank.

6. In a box blank making machine, the 85 combination of a chain, carrier-blocks arranged to be positively actuated by said chain for moving a blank forward, and a second chain normally moving faster than said first-named chain constructed and arranged to move said carrier-blocks successively forward, when released from engagement with one blank, into position for forwarding another blank.

7. In a box blank making machine, the 95 combination of an endless chain, a carrier-block provided with a pawl arranged to engage said chain whereby said chain drives said carrier-block positively forward for forwarding a blank, and a faster-moving 100 endless chain constructed and arranged to be moved alongside of said carrier-block in its forward movement with said first-named chain, said second-named chain being provided at one or more points therealong with 105 means for yieldingly engaging said carrier-block for moving said block, after being released from engagement with the blank, again into position to engage said first-named chain.

8. In a box blank making machine, the combination of an endless slideway, a carrier-block adapted to slide therealong, an endless chain constructed and arranged to have yielding connection with said carrier-block for moving said block about said slideway, and a second endless chain extending along a portion of said slideway arranged to move said carrier-block positively along that portion of the slideway when the 120 yielding connection between said block and said first-named chain has become broken.

9. In a box blank making machine, the combination of an endless slideway, a carrier-block adapted to slide therealong, an 125 endless chain constructed and arranged to have yielding connection with said carrier-block for moving said block about said slideway, and an intermittently-driven endless chain extending along a portion of said slide- 130

way arranged to move said carrier-block positively along that portion of the slideway when the yielding connection between said first-named chain and said block has become broken.

10. In a box blank making machine, the combination of an endless slideway, a carrier-block adapted to slide therealong, an endless chain constructed and arranged to have yielding connection with said carrier-block for moving said block about said slideway, and a slower-moving endless chain extending along a portion of said slideway arranged to move said carrier-block positively 70 along that portion of the slideway when the yielding connection between said first-named chain and said block has become broken.

11. In a box blank making machine, the combination of an endless slideway, a carrier-block adapted to slide therealong, an endless chain constructed and arranged to have yielding connection with said carrier-block for moving said block about said slideway, and an intermittently-driven endless 25 chain extending along a portion of said slideway having an effective slower rate of movement than said first-named chain arranged to move said carrier-block positively along that portion of the slideway when the 30 yielding connection between said first-named chain and said block has become broken.

12. In a box blank making machine, the combination of a carrier-block, positively-driven means constructed and arranged to have yielding connection with said carrier-block for moving it forward, positively-acting means arranged to move said block forward when the yielding connection between said block and said first-named forwarding 35 means has become broken, and means for preventing the carrier-block from rebounding when the yielding connection between the block and said first-named forwarding means is broken.

40. 13. In a box blank making machine, the combination of a carrier-block provided with a pawl, positively-driven means arranged to have yielding connection with said carrier-block for moving it forward, positively-acting means arranged to move said block forward when the yielding connection between said block and said first-named forwarding 45 means has become broken, and a rack with which the pawl carried by said carrier-block is arranged to engage for preventing the carrier-block from rebounding when the yielding connection between the block and said first-named forwarding means is broken.

50. 14. In a box blank making machine, the combination of an endless slideway, a carrier-block adapted to slide therealong and provided with a pawl, an endless chain constructed and arranged to have yielding connection with said carrier-block for moving

55 said block about said slideway, a second endless chain extending along a portion of said slideway arranged to move said carrier-block positively along that portion of the slideway when the resistance to the forward movement of the carrier-block has become so great as to cause its yielding connection with the first-named chain to become broken, and a rack with which the pawl carried by said carrier-block is arranged to engage for preventing the carrier-block from rebounding when the yielding connection between the block and said first-named chain is broken.

15. In a box blank making machine, the combination of an endless slideway, a carrier-block adapted to slide therealong, two endless chains one at each side of said slideway arranged to be revolved in unison and to have yielding connection with said carrier-block for moving said block about said slideway, and a third endless chain extending along a portion of said slideway arranged to move said carrier-block positively along that portion of the slideway when the 75 yielding connection between said block and said first-named chains has become broken.

16. In a box blank making machine, the combination of a carrier-block, an endless guide therefor, an endless chain extending 80 adjacent to said guide, and a plurality of connecting devices carried by said chain at intervals therealong arranged to yieldingly engage said carrier-block for moving it along said guide.

17. In a box blank making machine, the combination of a carrier-block having a spring-seated pin extending therefrom, an endless guide for said block, an endless chain extending adjacent to said guide, and 85 a lug on said chain arranged to engage said spring-seated pin for moving said block along said guide, one of said engaging members having a beveled engaging face whereby the connection between said chain and 90 said block is adapted to be broken.

18. In a box blank making machine, the combination of a carrier-block having a spring-seated pin extending therefrom, an endless guide for said block, an endless 95 chain extending adjacent to said guide, and a plurality of lugs spaced along said chain, any one of which lugs is arranged to engage said spring-seated pin for moving said block along said guide, said lugs and said pin having beveled engaging faces whereby the connection between said chain and said block is 100 adapted to be broken.

19. In a box blank making machine, the combination of a carrier-block, an endless 105 guide therefor, two endless chains one at each side of said guide, means for driving said chains in unison, and oppositely-disposed lugs carried by said chains adapted to engage said carrier-block for moving said 110

block along said guide, the connection between said chains and said block through said lugs being a yielding connection.

20. In a box blank making machine, the combination of a carrier-block having spring-seated pins extending therefrom, an endless guide for said block, two endless chains one at each side of said guide, means for driving said chains in unison, and oppositely-disposed lugs carried by said chains adapted to engage said spring-seated pins for moving said block along said guide, said lugs and said pins having beveled engaging faces whereby the connection between said chains and said block is adapted to be broken.

21. In a box blank making machine, the combination of a carrier-block having spring-seated pins extending therefrom, an endless guide for said block, two endless chains one at each side of said guide, means for driving said chains in unison, oppositely-disposed lugs carried by said chains adapted to engage said spring-seated pins for moving said block along said guide, said lugs and said pins having beveled engaging faces whereby the connection between said chains and said block is adapted to be broken, and means for holding said chains against lateral movement away from each other.

22. In a box blank making machine, the combination of two side-plates spaced a small distance apart and providing slideways between them, one at their upper edges and one at their lower edges, means at each end for connecting the upper and the lower slideways for forming a continuous endless slideway, a carrier-block slidably mounted in said slideway, and an endless chain constructed and arranged to have yielding connection with said block for moving it about said slideway.

23. In a box blank making machine, the combination of two side-plates spaced a small distance apart and providing slideways between them, one at their upper edges and one at their lower edges, an extension for the outer side-plate at each end thereof provided with flanges approximately semi-circular in shape, circumferentially grooved drums revolvably mounted on said extensions within said flanges whereby the upper and lower slideways are connected to form an endless slideway, means for rotating said drums, sprocket-chains mounted on sprocket-wheels carried by said drums on opposite sides of said slideway, a carrier-block provided with a pawl slidably mounted in said slideway, and constructed and arranged to have yielding connection with said chains for movement through said slideway, a third endless chain mounted between said two side-plates, and means for intermittently driving said third chain, said third chain

being arranged to positively drive said carrier-block through the medium of the pawl carried by said block.

24. In a box blank making machine, the combination of two slideways for the cleats of a blank properly spaced away from each other, means for forwarding the cleats in said slideways in unison, and frictionally operated means for steadyng the cleats in the slideways for the staple driving operation, comprising a roller adjacent to each slideway adapted to contact a cleat forwarded along the slideway, and positively-acting means for causing said two rollers to rotate in unison.

25. In a box blank making machine, the combination of two slideways for the cleats of a blank properly spaced away from each other, means for forwarding the cleats in said slideways in unison, and means adapted to grip said cleats as they pass the staple driving position for steadyng them in the slideways, comprising a plurality of rollers adjacent to each slideway adapted to have successive contact with a cleat forwarded along the slideway, and positively-acting means for causing the rollers adjacent to each slideway to rotate in unison.

26. In a box blank making machine, the combination of two slideways for the cleats of a blank properly spaced away from each other, means for forwarding the cleats in said slideways in unison, a plurality of rollers adapted to frictionally engage said cleats for holding them in proper position in each slideway as the cleats pass the staple driving position, and means acting independently of the frictional engagement of said rollers with said cleats for causing all of said rollers to rotate in unison.

27. In a box blank making machine, the combination of two slideways for the cleats of a blank properly spaced away from each other, means for forwarding the cleats in said slideways in unison, rollers adapted to frictionally engage said cleats for holding them in proper position in the slideways as they pass the staple driving position, and means for causing said rollers to rotate in unison.

28. In a box blank making machine, the combination of a chain, means for driving said chain continuously at a constant speed, carrier-blocks adapted to be actuated by said chain for moving a blank forward in the process of formation, a faster-moving chain adapted to move said carrier-blocks, when released from engagement with one blank, into operative position for forwarding another blank, and means for changing the speed of the faster-moving chain relative to the speed of the first-named chain.

29. In a machine for making wire bound box blanks, the combination of means for forwarding a blank, means for intermit-

- tently advancing a staple wire, means for forming a staple out of the staple wire intermittently fed thereto and for driving such staple into said blank at a certain predetermined staple driving position, spacing-blocks between each two adjacent cleats of the blanks, cams carried by said spacing-blocks, and means actuated by said cams successively for throwing out of operation 5 said staple wire advancing means as the joints between adjacent blank sections successively pass the staple driving position.
30. In a machine for making wire bound box blanks, the combination of means for 10 forwarding a blank comprising carrier-blocks adapted to move forward the cleats of the blank, means for intermittently advancing a staple wire, means for forming a staple out of the staple wire intermittently 15 fed thereto and for driving such staple into said blank at a certain predetermined staple driving position, cams carried by said carrier-blocks, and means actuated by said cams successively for throwing out of operation 20 said staple wire advancing means as the joints between adjacent cleats of said blank successively pass the staple driving position.
31. In a machine for making wire bound box blanks, the combination of means for 25 forwarding a blank, a transversely-extending shaft, staple wire advancing devices mounted on said shaft and operated by the rotation thereof, pawl and ratchet mechanism for intermittently rotating said shaft, means for forming staples out of the staple 30 wires intermittently fed thereto and for driving such staples into said blank at a certain predetermined staple driving position, and a collar mounted on said shaft adjacent to the ratchet-wheel by which said shaft is 35 rotated and arranged to be rocked into engagement with said pawl for throwing the pawl out of operative position, a cam carried forward with said blank, and means actuated by said cam for rocking said collar for 40 holding said pawl out of operative position as a joint between adjacent blank sections passes the staple driving position.
32. In a machine for making wire bound 45 box blanks, the combination of means for forwarding a blank past a predetermined staple driving position, means for driving staples in said blank in successive positions as the blank is forwarded, a lever pivotally 50 mounted on a movable fulcrum, means for reciprocating said lever, means for adjusting the position of said fulcrum relative to said lever for varying the operative stroke of the lever, and operative connections be- 55 tween said lever and said blank-forwarding means for actuating said blank-forwarding means whereby an adjustment of the position of said fulcrum serves to vary the amount of forward movement of said blank 60 between successive staple driving operations.
33. In a machine for making wire bound box blanks, the combination of means for forwarding a blank past a predetermined staple driving position, means for driving staples in said blank in successive positions 65 as the blank is forwarded, a lever pivotally mounted on a movable fulcrum, means connected with one end of said lever for reciprocating the lever, means for adjusting the position of said fulcrum relative to the lever 70 for varying the operative stroke of the lever, and operative connections between the other end of said lever and said blank-forwarding means for actuating said blank-forwarding means. 75
34. In a machine for making wire bound box blanks, the combination of means for forwarding a blank past a predetermined staple driving position, means for driving staples in said blank in successive positions 80 as the blank is forwarded, a pivotally-mounted arm, a fulcrum-block revolubly mounted on said arm, a lever slidably mounted on said fulcrum-block, means for reciprocating said lever, means for adjusting the position of said arm relative to said lever for varying the operative stroke of the lever, and operative connections between said lever and said blank-forwarding means for actuating said blank forwarding means where- 85 by an adjustment of said arm relative to said lever serves to vary the amount of forward movement of said blank between successive staple driving operations. 90
35. In a machine for making wire bound 95 box blanks, the combination of means for forwarding a blank past a predetermined staple driving position, means for driving staples in said blank in successive positions as the blank is forwarded, a pivotally-mounted arm, a fulcrum-block revolubly mounted on said arm, a lever having a longitudinally-extending slot in which said fulcrum-block is slidably mounted, a link connected with said lever and adapted to swing 100 relative thereto for permitting the lever to be reciprocated on its fulcrum but adapted to limit the longitudinal movement of the lever, means for reciprocating said lever, means for adjusting the position of said arm relative to said lever for varying the operative stroke of the lever, and operative connections between said lever and said blank-forwarding means for actuating said blank-forwarding means whereby an adjustment 105 of said arm relative to said lever serves to vary the amount of forward movement of said blank between successive staple driving operations. 110
36. In a machine for making wire bound 115 box blanks, the combination of means for forwarding a blank past a predetermined staple driving position, means for driving staples in said blank in successive positions as the blank is forwarded, a lever pivotally 120 mounted on a movable fulcrum, means for reciprocating said lever, means for adjusting the position of said fulcrum relative to said lever for varying the operative stroke of the lever, and operative connections between said lever and said blank-forwarding means for actuating said blank-forwarding means whereby an adjustment of the position of said fulcrum serves to vary the amount of forward movement of said blank between successive staple driving operations. 125
37. In a machine for making wire bound 130 box blanks, the combination of means for forwarding a blank past a predetermined staple driving position, means for driving staples in said blank in successive positions as the blank is forwarded, a lever pivotally

- mounted on a movable fulcrum, an arm by an adjustment of which the position of the fulcrum of said lever is controlled, means connected with one end of said lever for reciprocating the lever, an adjusting rod adapted to be held in fixed position relative to said lever and having screw-threaded connection with said arm for adjusting the position of said arm relative to said lever 5 whereby the operative stroke of said lever may be varied, and operative connections between the other end of said lever and said blank-forwarding means for actuating said blank-forwarding means.
- 15 37. In a machine for making wire bound box blanks, the combination of means for forwarding a blank past a predetermined staple driving position, means for driving staples in said blank in successive positions 20 as the blank is forwarded, said blank forwarding means comprising an arm by successive strokes of which in opposite directions the extent of movement of the blank between successive operations of the staple- 25 driving means is varied, and means automatically actuated at intervals during the forward movement of the blank for swinging said arm.
38. In a machine for making wire bound 30 box blanks, the combination of means for forwarding a blank past a predetermined staple driving position, means for driving staples in said blank in successive positions as the blank is forwarded, said blank for- 35 warding means comprising a rotary member by successive half rotations of which the extent of movement of the blank between successive operations of the staple driving means is varied, and means for giving said 40 rotary member successive half rotations as desired for varying the movement of the blank between stitches.
39. In a machine for making wire bound 45 box blanks, the combination of means for forwarding a blank past a predetermined staple driving position, means for driving staples in said blank in successive positions as the blank is forwarded, said blank for- 50 warding means comprising a rotary member by successive half rotations of which the extent of movement of the blank between successive operations of the staple driving means is varied, means for adjusting the difference between successive forward move- 55 ments of the blank, and means for giving said rotary member successive half rotations as desired for varying the movement of the blank between stitches.
40. In a machine for making wire bound 60 box blanks, the combination of means for forwarding a blank past a predetermined staple driving position, means for driving staples in said blank in successive positions as the blank is forwarded, said blank for- 65 warding means comprising an arm by suc- cessive strokes of which in opposite direc- 70 tions the extent of movement of the blank between successive operations of the staple-driving means is varied, a rotary member by successive partial revolutions of which said arm is actuated, and means automatically actuated at intervals during the forward movement of the blank for giving said rotary member successive operative partial revolutions. 75
41. In a machine for making wire bound box blanks, the combination of means for forwarding a blank past a predetermined staple driving position, means for driving staples in said blank in successive positions 80 as the blank is forwarded, said blank for- warding means comprising a rotary member by successive half rotations of which the extent of movement of the blank between successive operations of the staple driving means is varied, a clutch by successive actuations of which said rotary member is given successive half rotations, and means automatically actuated at intervals during the forward movement of the blank for throw- 85 ing said clutch into operation. 90
42. In a machine for making wire bound box blanks, the combination of means for forwarding a blank past a predetermined staple driving position, means for driving staples in said blank in successive positions 95 as the blank is forwarded said blank for- warding means comprising an arm by suc- cessive strokes of which in opposite direc- 100 tions the extent of movement of the blank between successive operations of the staple- driving means is varied, a rotary member by successive partial revolutions of which said arm is actuated, a clutch by successive actuations of which said rotary member is given successive operative partial revolutions, and means automatically actuated at intervals 105 during the forward movement of the blank for throwing said clutch into operation. 110
43. In a machine for making wire bound box blanks, the combination of means for forwarding a blank past a predetermined staple driving position, means for driving staples in said blank in successive positions 115 as the blank is forwarded, said blank for- warding means comprising an arm by suc- cessive strokes of which in opposite directions the extent of movement of the blank between successive operations of the staple-driving means is varied, a rotary member by suc- 120 cessive partial revolutions of which said arm is actuated, and a clutch by successive actuations of which said rotary member is given successive operative partial revolutions, and a lever actuated at intervals in timed relation 125 to the forward movement of the blank adapted to throw said clutch into operation for operating said arm for varying the forward movement of the blank between stitches. 130

44. In a machine for making wire bound box blanks, the combination of means, comprising suitably-positioned cams, for forwarding a blank past a predetermined staple driving position, means for driving staples in said blank in successive positions as the blank is forwarded, and automatically-acting means actuated by said cams for alternately shortening and lengthening the movement of the blank between staple driving operations as successive sections of said blank are brought into staple driving position.
45. In a machine for making wire bound box blanks, the combination of means, comprising suitably-positioned cams, for forwarding a blank past a predetermined staple driving position, means for driving staples in said blank in successive positions as the blank is forwarded, and automatically-acting means actuated by said cams for shortening the forward movement of the blank between successive staple driving operations as a narrow section of the blank is carried past the staple driving position, and for again lengthening the forward movement as a wide section of the blank is carried past the staple driving position.
46. In a machine for making wire bound box blanks, the combination of means comprising carrier-blocks for forwarding a blank past a predetermined staple driving position, means for driving staples in said blank in successive positions as the blank is forwarded, automatically-acting means actuated by the forward movement of said carrier-blocks for alternately increasing and decreasing the extent of movement of the blank between successive operations of the staple-driving means and a lever by a stroke of which the extent of variation may be regulated.
47. In a machine for making wire bound box blanks, the combination of means comprising carrier-blocks for forwarding a blank past a predetermined staple driving position, means for driving staples in said blank in successive positions as the blank is forwarded, and automatically-acting means actuated by the forward movement of said carrier-blocks for shortening the forward movement of the blank between successive staple driving operations as a narrow section of the blank is carried past the staple driving position and for again lengthening the forward movement as a wide section of the blank is carried past the staple driving position.
48. In a machine for making wire bound box blanks, the combination of means comprising carrier-blocks for forwarding a blank past a predetermined staple driving position, said carrier-blocks being provided with cams, means for driving staples in said blank in successive positions as the blank is forwarded, and automatically-acting means actuated by the cams mounted on said carrier-blocks for varying the extent of movement of the blank between successive staple driving operations.
49. In a machine for making wire bound box blanks, the combination of means for forwarding a blank past a predetermined staple driving position, spacing-blocks adapted to space the cleats of a blank in proper position relative to each other in their forward movement, means for driving staples in said blank in successive positions as the blank is forwarded, and automatically-acting means actuated at intervals by the forward movement of said spacing-blocks for adjusting the blank forwarding means for varying the extent of movement of the blank between successive operations of the staple-driving means.
50. In a machine for making wire bound box blanks, the combination of means for forwarding a blank past a predetermined staple driving position, means for driving staples in said blank in successive positions as the blank is forwarded, a rotatable member, means actuated by successive predetermined rotations of said rotatable member for alternately shortening and lengthening the movements of the blank between successive staple driving operations, and automatically-acting means actuated at suitable intervals during the forward movement of the blank for giving said rotatable member an operative movement.
51. In a machine for making wire bound box blanks, the combination of means for forwarding a blank past a predetermined staple driving position, means for driving staples in said blank in successive positions as the blank is forwarded, a rotatable member, means actuated by successive half revolutions of said rotatable member for alternately shortening and lengthening the movements of the blank between successive staple driving operations, and automatically-acting means actuated at suitable intervals during the forward movement of the blank for giving said rotatable member a half revolution.
52. In a machine for making wire bound box blanks, the combination of means for forwarding a blank past a predetermined staple driving position, means for driving staples in said blank in successive positions as the blank is forwarded, a rotatable member, means actuated by successive half revolutions of said rotatable member for alternately shortening and lengthening the movement of the blank between successive staple driving operations, and automatically-acting means actuated by the forward movement of the blank for giving said rotatable member a half revolution as each joint between adjacent blank sections passes the staple driving position.
53. In a machine for making wire bound box blanks,

- box blanks, the combination of means comprising carrier-blocks for forwarding a blank past a predetermined staple driving position, means for driving staples in said blank in successive positions as the blank is forwarded, a rotatable member, means actuated by successive half revolutions of said rotatable member for alternately shortening and lengthening the movements of the blank between successive staple driving operations, and automatically-acting means actuated by the forward movement of the carrier-blocks for giving said rotatable member a half revolution as each joint between adjacent blank sections passes the staple driving position.
54. In a machine for making wire bound box blanks, the combination of means for forwarding a blank past a predetermined staple driving position, spacing-blocks adapted to space the cleats of a blank in proper position relative to each other in their forward movement, means for driving staples in said blank in successive positions as the blank is forwarded, a rotatable member, and automatically-acting means actuated by the forward movement of the spacing-blocks for giving said rotatable member a half revolution as each joint between adjacent blank sections passes the staple driving position.
55. In a machine for making wire bound box blanks, the combination of means for forwarding a blank past a predetermined staple driving position, means for driving staples in said blank in successive positions as the blank is forwarded, a lever pivotally mounted on a movable fulcrum, means for reciprocating said lever, operative connections between said lever and said blank for warding means for actuating said blank-forwarding means, a rotatable member, means connecting said movable fulcrum with said rotatable member eccentrically of said rotatable member whereby successive half revolutions of said rotatable member serve to shift said fulcrum relatively to the lever for varying the stroke of said lever and varying the forward movement of the blank between successive staple driving operations, and automatically-acting means actuated by the forward movement of the blank for giving said rotatable member a half revolution as each joint between adjacent blank sections passes the staple driving position.
56. In a machine for making wire bound box blanks, the combination of means for forwarding a blank past a predetermined staple driving position, means for driving staples in said blank in successive positions as the blank is forwarded, a pivotally-mounted arm, a fulcrum-block revolvably mounted on said arm, a lever slidably mounted on said fulcrum-block, means connected with one end of said lever for reciprocating the lever, operative connections be-
- tween the other end of said lever and said blank-forwarding means for actuating said blank-forwarding means, a rotatable member, means connecting said arm with said rotatable member eccentrically of said rotatable member whereby successive half revolutions of said rotatable member serve to shift said fulcrum relatively to the lever for varying the stroke of said lever and varying the forward movement of the blank between successive staple driving operations, and automatically-acting means actuated by the forward movement of the blank for giving said rotatable member a half revolution as each joint between adjacent blank sections passes the staple driving position.
57. In a machine for making wire bound box blanks, the combination of means for forwarding a blank past a predetermined staple driving position, means for driving staples in said blank in successive positions as the blank is forwarded, a rotatable member, means actuated by successive half revolutions of said rotatable member for alternately shortening and lengthening the movements of the blank between successive staple driving operations, means for rotating said rotatable member comprising a clutch arranged to stop the rotation of said rotatable member at the end of a single half revolution, and automatically-acting means actuated by the forward movement of the blank for throwing said clutch into operation for giving said rotatable member a half revolution as each joint between adjacent blank sections passes the staple driving position.
58. In a machine for making wire bound box blanks, the combination of means for forwarding a blank past a predetermined staple driving position, means for driving staples in said blank in successive positions as the blank is forwarded, a rotatable member, means actuated by successive half revolutions of said rotatable member for alternately shortening and lengthening the movements of the blank between successive staple driving operations, means for rotating said rotatable member comprising a clutch arranged to stop the rotation of said rotatable member at the end of a single half revolution, means by an operative stroke of which said clutch is started in operation, means actuated by the forward movement of the blank for giving said clutch-starting means an operative stroke, and means for throwing said clutch-starting means out of operative clutch-starting position whereby the clutch is permitted to stop the rotation of said rotatable member.
59. In a machine for making wire bound box blanks, the combination of means for forwarding a blank past a predetermined staple driving position, means for driving staples in said blank in successive positions as the blank is forwarded, a rotatable mem-

ber, means actuated by successive half revolutions of said rotatable member for alternately shortening and lengthening the movements of the blank between successive staple driving operations, means for rotating said rotatable member comprising a clutch arranged to stop the rotation of said rotatable member at the end of a single half revolution, means by an operative stroke of which 5 said clutch is started in operation, means actuated by the forward movement of the blank for giving said clutch-starting means an operative stroke, and means actuated by the rotation of the clutch for throwing said 10 clutch-starting means out of operative clutch-starting position whereby the clutch is permitted to stop the rotation of said rotatable member.

60. A machine for use in making wire-bound boxes comprising, in combination, a work support; fastener-setting mechanism; means to cause relative step-by-step progression between said mechanism and the work; and automatically adjustable means to control the extents of said step movements. 20

61. A machine for use in making wire-bound boxes comprising, in combination, a work support; fastener-setting mechanism; means to cause relative progression between 30 said mechanism and the work; and automatically adjustable means controlling said progression to vary the distance between fasteners.

62. A machine for use in making wire-bound boxes comprising, in combination, a work support; fastener-setting mechanism; means to present successive fastener-receiving points on the work to said mechanism; and automatically adjustable means controlling 40 said work-presenting means to vary the normal spacing of fasteners.

63. A machine for use in making wire-bound boxes comprising, in combination, means to receive and position in foldable relationship a plurality of box sections; fastener-setting mechanism for wiring said sections together; means to cause relative step-by-step progression between said mechanism and the work to locate fasteners at intervals 45 in the work; and automatically adjustable controlling means therefor, constructed and arranged to vary the spacing of fasteners in alternate box sections. 50

64. A machine for use in making boxes comprising, in combination, work-forwarding means for positioning and advancing box sections; fastener-setting mechanism for driving fasteners at intervals into the box sections; means for causing relative step-by-step progression between said mechanism and the box sections; and automatically adjustable means controlled by the work-forwarding means for changing the extent of 60 step movements as each box section is presented to the fastener-setting mechanism. 65

65. A machine for use in making boxes comprising, in combination, means to position box parts; fastener-setting mechanism; and feeding means to cause relative progression therebetween, comprising moving 70 means adapted to yieldingly engage the positioning means, and moving means adapted to positively engage the positioning means.

66. A machine for use in making boxes comprising, in combination, work-forwarding 75 means; fastener-setting mechanism; and means to cause relative progression therebetween, comprising a yielding driving means and a positive driving means, both adapted to engage the work-forwarding 80 means.

67. A machine for use in making boxes comprising, in combination, work-forwarding means; fastener-setting mechanism; and means to cause relative progression therebetween, including means to positively advance the work-forwarding means and a separate and independent means to yieldingly advance the work-forwarding means. 85

68. A machine for use in making boxes comprising, in combination, work-forwarding means; fastener-setting mechanism; and means to cause relative progression therebetween, including means to advance the work-forwarding means step by step during a portion 90 of its travel and a separate and independent means to advance the work-forwarding means constantly during another portion of its travel. 95

69. A machine for use in making boxes 100 comprising, in combination, work-forwarding means; fastener-setting mechanism; and means to cause relative progression between said mechanism and the work, including means to positively engage and advance the 105 work-forwarding means and means to yieldingly engage and advance the work-forwarding means, said positive engaging means and said yielding engaging means being constructed and arranged to operate 110 alternately on the work-forwarding means in the operation of the machine.

70. A machine for use in making boxes comprising, in combination, work-forwarding means; fastener-setting mechanism; and 115 means to cause relative progression between said mechanism and the work, including means to engage and positively feed the work-forwarding means past the fastener-setting mechanism and means to engage and 120 deliver the work-forwarding means to said positive feeding means.

71. A machine for use in making boxes comprising, in combination, a work support; fastener-setting mechanism; a plurality of 125 work-forwarding devices each adapted to engage the rear edge of a box section; means to positively engage each device and feed it past the fastener-setting mechanism; and means to yieldingly engage each device after 130

it passes the fastener-setting mechanism and return it to position to engage the rear edge of another box section.

72. A machine for use in making boxes comprising, in combination, work-forwarding means for advancing box parts; means to positively advance said work-forwarding means when in engagement with a box part; and means to advance the work-forwarding means, when not in engagement with a box part, into position for forwarding another box part.

73. In a box blank machine, a flexible work holder for spacing and feeding a plurality of foldably related box sections comprising a plurality of members, each adapted to engage and push a box section; means

to positively engage and advance each of said members when in engagement with a box section; and means to engage each of 20 said members when released from engagement with a box section and advance it into position for forwarding another section.

74. In a box blank machine, a flexible work holder for spacing and feeding a plurality of foldably related box sections comprising a plurality of members, each adapted to engage and push a box section; means to positively advance each of said members during a portion of its travel; and a separate and independent means to yieldingly advance said member during another portion of its travel.

CHARLES EIKLER.
